UNITED STATES PATENT OFFICE.

LEONIDAS D. WEST, OF DENVER, COLORADO.

DOORCHECK.

Application filed February 16, 1923. Serial No. 619,400.

To all whom it may concern:

Be it known that I, LEONIDAS D. WEST, a citizen of the United States, residing at Denver, the city and county of Denver, and 5 State of Colorado, have invented certain new and useful Improvements in Door-checks; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates to door checks of the type which has the operating mechanism located beneath the floor.

I am aware that several different types of door checks, adapted to be concealed in 20 the floor, have been made and sold, but none of them have gone into general use, owing to various features of construction which make them objectionable.

It is the object of this invention to produce 25 a door check of the type referred to that shall have several distinct advantages over the prior art as it is known to me.

One object of this invention is to the production of a door check of the type referred 30 to that can be applied to any existing door pivotally mounted on ordinary hinges and thus obviate the necessity of rehanging old doors on different kinds of hinges, as well as the necessity of providing special hinges 35 for new doors.

It is another object of the invention to produce a door check that can be located to the side of the door and in the floor as distinguished from those which must be located 40 directly underneath the door. By this provision the mechanism can be reached at any time without maintaining the door in open position.

A further object of this invention is to 45 provide an arrangement and combination of parts that can be assembled and disassembled and in which the parts can be made readily accessible for the purpose of effecting repairs.

50 Other and different objects will appear as the description proceeds.

In order to more fully describe my invention, reference will be had to the accompanying drawings, in which:

55 Fig. 1 is a perspective view showing the lower portion of a door and a door-frame,

together with a portion of the floor parts of the floor, as well as part of the casing enclosing the mechanism being broken away to show the mechanism of the door check. 60

Fig. 2 is a top plan view of the spring casing.

Fig. 3 is a section taken on line 3—3, Fig. 4.

Fig. 4 is a section taken on line 4—4, 65 Fig. 2.

Fig. 5 is a side elevation of the dash-pot with a portion thereof broken away to show the piston rod, piston and by-pass.

Fig. 6 is a view similar to that of Fig. 1, 70 but showing a modification.

Fig. 7 is a plan view looking down on the parts shown in Fig. 6, a part of the casing being broken away to better show the construction; and 75

Fig. 8 is a view showing a slightly modified form of connecting means.

The same reference characters (will be used to designate the same parts throughout the several views.

Numeral 1 designates an ordinary door which is pivotally mounted in a door-frame 2 by means of hinges 3. Located in an opening in the floor on the side of the door to which the latter swings is a metal casing 4 which is made in the form of rectangular box having no bottom. An opening 5 is provided in the upper side of the box and provided with flanges 6 which are adapted to support a cover (not shown). 90

Secured to the right hand end of the box 4 (Fig. 1) is a spring casing 7 which is cylindrical in shape and provided at one side with a bracket 8 having at its end a flange 9 which can be bolted to the end of the box 95 4. The casing 7 has a bottom member 10 provided centrally thereof with an opening for the reception of a shaft 11 to whose lower end is non-rotatably secured a crank 12. The casing 7 has a slot 13 in its side 100 for the reception of one end of a spiral spring 14. The outer end of spring 14 has 2 parallel cuts which form three fingers 15, 16 and 17, two of which are bent in one direction and one in the other direction. 105 These fingers serve to hold the end of the spring in place in the manner shown in Figs. 3 and 4.

The inner end of the spring 14 is bent into what may be loosely designated as a hook 18 which engages one corner of the non-circular central portion 19 of the shaft 11. 110

As the spring is wound the coils tend to contract and keep the end from slipping off the bolt. A cover 20 is threadedly or otherwise secured to the casing 7 in the manner shown in Fig. 4. This cover has a central opening which forms a bearing for the upper end of the shaft 11. Shaft 11 is provided near its upper end with a flange 21 which projects through a suitable opening in the top of box 4. Above the flange 21 the shaft 11 has a portion 22 of reduced diameter. This portion has an axial opening 23 of square or other non-circular shape, which is adapted to receive the end of a correspondingly shaped wrench. Flange 21 has a number of holes 24, the purpose of which will hereinafter appear. A lever 25 is provided at one end with a hole adapted to receive the circular portion 22 of the shaft. A screw 26 extends through the lever and into one of the holes 24 and serves as a means for adjusting the relative positions of the shaft and lever. The lever 25 has an elbow 27 and has secured to the upper side thereof and near the outer end a roller 28 which cooperates with a channel-shaped guide 29 in the manner shown in Figs. 1 and 4. The guide 29 is secured to the bottom of the door and consequently when the door opens or closes the lever 25 is moved and rotates the shaft 11 and crank 12. The spring is, of course, attached to the casing and the shaft in such a manner that it will resist the opening of the door. In order to produce a retarding action for controlling the closing of the door, I hinge a dash-pot *d* to the left hand end of box 4 (Fig. 1). The dash-pot is of more or less conventional construction having a cylinder; a removable cylinder head 31; a piston 32 provided with a check valve 33 which permits liquid to flow from the right hand end of the cylinder to the left hand end (Fig. 5), but not in the reverse direction. A by-pass 34 extends from one end of the cylinder to the other and has intermediate thereof a valve 35, by means of which the capacity of the by-pass can be controlled. A plug 36 permits the cylinder to be filled with a non-congealable lubricating fluid such as a mixture of alcohol, glycerine and water. A piston rod 37 extends from the piston 32 through the packing box 38 and has its end pivotally connected to the end of crank 12 by means of a belt 39. The parts are adjusted in such a manner that when the door is closed the piston occupies a position near the left hand end of the cylinder (Fig. 5) and the crank arm 12 is of such length that when the door is opened 180 degrees, the piston has been moved to a position near the right hand end of the cylinder. It is evident that if we assume the parts as occupying the position shown in Figs. 1 and 5 and then open the door, the action between the guide 29 and the roller 28 on the end of the lever 25 will cause the latter to be rotated about its pivot and as the shaft 11 is non-rotatably connected thereto, the shaft will also be rotated in a direction to tension the spring. 70 As the shaft is rotated through the action of opening the door, the crank 12, which is non-rotatably connected thereto, will move the piston 32 towards the right of the dash-pot (Fig. 5). When the force tending to 75 open the door ceases, the action of the spring will tend to close the same and this closing action is retarded by the dash-pot in a manner perfectly apparent. The tension of the spring can be adjusted by applying a suitable wrench to the socket 23, removing the screw 26 and either disconnecting the crank arm 12 from the piston rod or from the shaft. When the spring has been properly tensioned, the screw 26 is inserted into the 80 openings 24 and the crank 12 properly adjusted and secured to the shaft. The device can be used for either right or left hand doors by reversing the spring and relative angular position of the levers 12 and 25. 85 A different lever 25 is usually employed for a left hand door than for a right hand door, although the lever 25 can readily be so designed that it is reversible and can be used in connection with either type of door. 90

Since the box 4 is located in the floor on one side of the door, it is readily accessible. By removing screw 26, the lever 25 can be removed from shaft 11 and the box removed from its recess in the floor, thus 100 enabling repairs to be quickly and conveniently made.

In Figs. 6 and 7 I have shown a modification in which a different type of spring is employed. I have shown secured to one side 105 of the door a guide 45 which performs the same function as the guide 29 and cooperates with a pin or roller 46, carried on the free end of the lever 25, which may be an exact duplicate of the corresponding lever in 110 Fig. 2. The top of box 4 is perforated to provide a bearing for the lug 47 which is integral with the crank 48. Lever 25 is secured to the end of lug 47 in exactly the same manner as it is secured to shaft 11. A dash-pot *d* which is identical with the one described above is hinged to the left hand end of the box 4 (Figs. 6 and 7). The piston rod is pivotally connected to the crank 48 intermediate the ends thereof so that when 115 the door opens and closes the piston will be caused to reciprocate in the cylinder, as above explained. Instead of the spring casing 7 and associated parts, I provide one or more helical tension springs 49 which have one end secured to the pin 50 which projects downwardly from the end of the crank 48. The other ends of springs 49 are secured to an adjustable member 51 that is secured to the end of a bar 52 which is slidably 120

125 130

mounted in holes in the lugs 53 which project downwardly from the side of box 4. A bolt 54 is threadedly connected to one of the lugs 53 and engages an opening in the part 51. By means of the bolt 54 the tension in the spring can be increased or decreased at will. I want to call particular attention to the fact that by the construction just explained, my door check can be made to hold the door open as well as closed. When the door is opened substantially 180 degrees, the pull of springs 49 will move to the other side of the center of the pivot 47 and will exert a force tending to hold the door open. The springs 49 can be made of any desired strength and one, two or more springs can be used.

In Fig. 8 I have shown a guide rod 55 which can be substituted for the guide 45. Rod 55 is supported at its ends by brackets 56. A bearing member 57 is slidable on the rod 55 and pivotally connected to the end of lever 25.

From the above, it will be apparent that I have produced a door check that can be readily attached to doors already hung and which does not require special hinges. My door check can be mounted in the floor by merely sawing out a hole of the proper size. The parts can be readily removed for repair or replacement and any repair can be done by anyone having the least familiarity with the use of tools.

Having now described my invention, what I claim as new is:

1. A door closing and retarding device comprising a supporting member adapted to be secured in an opening in the floor, said supporting member having an opening in its upper surface; a removable plate for closing said opening; a lever pivotally mounted near one end of the support and adapted to swing in a plane parallel to the upper surface thereof; a crank arm non-rotatably connected to said lever on the lower side of said support; a dash-pot operatively connected between the support and the crank, said dash-pot being adapted to retard the movement of the crank case and lever in one direction and permit free movement in the other direction; a resilient spring means secured to the end of said crank and adapted to move the lever against the retarding action of the dash-pot.

2. A door closing and retarding device comprising a supporting member adapted to be secured in place in the floor near a door, said support having an opening; a plate re-

movably secured to the opening; a crooked lever pivotally mounted in said support and adapted to swing in a plane parallel with the upper surface thereof; a crank arm non-rotatably secured to the lever and located beneath the support; a dash-pot pivotally connected to the crank arm and to the support; resilient means comprising helical tension springs secured to the crank arm at one end and to an anchoring means at the other end, said means being adapted to cause the lever to move against the retarding action of the dash-pot.

3. A door closing and retarding device comprising a plate-like supporting member adapted to be secured to the floor near a door, said supporting member having downwardly projecting flanges; an opening in said member; a removable plate adapted to cover said opening; a crank arm pivotally mounted in said support near one end thereof and adapted to swing in a plane parallel to the support, but below the same; a crooked lever adjustably secured to the crank arm and adapted to swing in a plane parallel to and above said support; a dash-pot secured to said support and to said crank arm and adapted to permit substantially free movement of the lever in one direction, but to retard the movement in the opposite direction a resilient spring means secured at one end to the end of the crank arm and at the other end to an adjustable anchor secured to the support; and means for moving said anchor whereby the tension of the springs can be adjusted.

4. A door closing and retarding device comprising a supporting member adapted to be secured in an opening in the floor, said opening being wholly in front of the door when the latter is in the closed position, a removable plate for closing said opening, a lever pivotally mounted on the support and adapted to swing in a plane parallel to the upper surface thereof, a crank arm non-rotatably connected to said lever at the lower side of the support, a dash pot operatively connected between the support and the crank, said dash pot being adapted to retard the movement of the crank and lever in one direction and permit free movement in the other direction, and spring means connected with said crank and adapted to move the lever against the retarding action of the dash pot.

In testimony whereof I affix my signature.

LEONIDAS D. WEST.
